UNITED STATES PATENT OFFICE.

WILLIAM DALTON AND WILLIAM E. WOODARD, OF SCHENECTADY, NEW YORK, ASSIGNEES
TO AMERICAN LOCOMOTIVE COMPANY, OF NEW YORK, N. Y., A CORPORATION OF NEW
YORK.

SPRING AND EQUALIZER SYSTEM FOR ELECTRIC LOCOMOTIVES.

No. 918,828.

Specification of Letters Patent.

Patented April 20, 1909.

Application filed September 19, 1908. Serial No. 453,769.

To all whom it may concern:

Be it known that we, WILLIAM DALTON and WILLIAM E. WOODARD, both of Schenectady, in the county of Schenectady and 5 State of New York, have jointly invented a certain new and useful Improvement in Spring and Equalizer Systems for Electric Locomotives, of which improvement the following is a specification.

10 The object of our invention is to provide a spring and equalizer system which shall be readily adaptable in electric locomotives of the designs approved in present practice and in the operation of which a substantially 15 greater degree of flexibility may be obtained than is practicable under the constructions heretofore used or proposed.

The improvement claimed is hereinafter fully set forth.

20 In the accompanying drawings: Figure 1 is a side view in elevation, of a portion of a spring and equalizer system for electric locomotives, illustrating an embodiment of our invention; Fig. 2, a plan or top view of the 25 same; Fig. 2^a, a transverse section, on the line X X of Fig. 1; Fig. 3, a side view, on an enlarged scale, of the end portion of a spring and its connections; Fig. 4, a view similar to Fig. 1, illustrating a modification of structural detail; Fig. 5, a plan or top view of the construction shown in Fig. 4; and Fig. 6, a transverse section, on the line Y Y of Fig. 4.

Referring first to Figs. 1 to 3 inclusive, our invention is herein illustrated as applied in an 35 electric locomotive having a main supporting frame comprising suitably cross connected bar side members, 1, of the standard type, which, with the mechanism carried thereon, are spring supported on a plurality 40 of wheels, 2, fixed upon axles, 3, the end journals of which rotate in journal boxes, 4, which are fitted between the members of pairs of pedestal jaws, 1^a, on the side frame members, with the capacity of vertical movement 45 of the latter, relatively to the journal boxes, in the ordinary manner.

A plate or leaf spring, 5, of semi-elliptic form, having its set or curvature in a vertical plane, is located above each of the frame 50 members, 1, over each of the journal boxes thereof, the central band, 5^a, of each spring, bearing, through a roller 5^b, on a vertical saddle, 6, the lower end of which bears on the

top of the journal box. Instead of the springs, 5, being connected, at their ends, to the frame members, or to equalizers thereon, in the same manner as in ordinary practice, in which the length of the spring is necessarily limited by that of the arms of the equalizers to which it is connected, the springs are, under our invention, extended so that the length of each spring between its end bearings is greater than the distance between the ends of the frame equalizers on opposite sides of the axle above which the spring is set. The springs are, preferably, extended to as great a length as the distances between the centers of the axles will permit, and the upper spring equalizer bars, 17, of substantially the same length as the extended springs, are located above each of them, and supported upon them, adjacent to their ends, by rollers, 5^c, which allow for the movement of the springs in their deflection. Double armed frame equalizers, 8, of the ordinary type, are pivoted, by pins, 8^a, to vertical standards or bearing pieces, 1^b, bolted to the frame members between the axles, and are coupled, by spring hangers 7, to the upper spring equalizer bars, 17. It will, of course, be understood that the spring hangers at the ends of the system are coupled at their lower ends, to pins on the frame members, there being no frame equalizers located beyond the end wheels and no necessity therefor.

It will be seen that by the increase in length of the springs which is rendered admissible by the above construction a much greater degree of flexibility is attained than in prior constructions, and, at the same time, there is no curtailment of the length of the frame equalizers, so that the latter operate with the same freedom and range of pivotal movement as heretofore.

Figs. 4 to 6 inclusive illustrate a structural modification in which the upper spring equalizer bars, 17, above specified, are dispensed with, and the springs are so connected to the frame equalizers as to enable the length of the springs to be increased to a still greater degree than in the instance first described. In this case, a single spring 5, and a pair of parallel springs, 55, are set above the journal boxes of alternate axles, the ends of the single springs, 5, extending between those of the pairs of parallel springs, 55,

which are located on opposite sides of the 5 springs 5. The ends of each of the single springs are coupled by spring hangers, 7, 7^b, to the ends of the two frame equalizers, 8, on opposite sides of the axle above which said 10 single spring is set, which are farther from said axle, the hangers, 7, being single and passing down between the springs, 55, and the hangers, 7^b, being double and coupled by pins, 7^a, to the hangers, 7, below which they 15 extend to the frame equalizers. The adjacent ends of the pairs of springs, 55, on each side of each single spring, are coupled, by spring hangers, 7^c, to the ends of the two 20 frame equalizers, 8, on opposite sides of the axle above which the single spring is set, which are nearer said axle. The effective 25 length of each spring is, therefore, under this construction, increased from the distance between the nearer end connections of the two frame equalizers on opposite sides of its axle, which it would be in ordinary practice, to that between the farther end connections of said two frame equalizers, that is to say, 30 is increased by the combined length of said two frame equalizers. The length of the frame equalizers themselves is unaffected, and they operate, in connection with the 35 springs, 5 and 55, in the usual manner. As in the instance first described, it will be understood that the spring hangers at the ends of the system, whether they be those of single springs or of pairs of springs, are coupled at their lower ends, to pins on the frame members, in the usual manner.

We claim as our invention and desire to secure by Letters Patent:

1. In a locomotive, the combination of a main supporting frame, a plurality of axles 40 on which said frame is carried with the capacity of relative vertical movement, double armed frame equalizers pivoted on the main supporting frame intermediate the axles, springs bearing centrally on the axle journals 45 and of greater length between their end bearings than the distance between adjacent frame

equalizers, and intermediate connections coupling said springs and frame equalizers.

2. In a locomotive, the combination of a main supporting frame, a plurality of axles 50 on which said frame is carried with the capacity of relative vertical movement, double armed frame equalizers pivoted on the main supporting frame intermediate the axles, springs bearing centrally on the axle journals 55 and of greater length between their end bearings than the distance between adjacent frame equalizers, and spring hangers coupling said springs and frame equalizers.

3. In a locomotive, the combination of a main supporting frame, a plurality of axles 60 on which said frame is carried with the capacity of relative vertical movement, double armed frame equalizers pivoted on the main supporting frame intermediate the axles, 65 springs bearing centrally on the axle journals and of greater length between their end bearings than the distance between adjacent frame equalizers, upper spring equalizer bars supported on the springs, adjacent to their 70 ends, and spring hangers coupled to said upper spring equalizer bars and to the frame equalizers.

4. In a locomotive, the combination of a main supporting frame, a plurality of axles 75 on which said frame is carried with the capacity of relative vertical movement, double armed frame equalizers pivoted on the main supporting frame intermediate the axles, springs bearing centrally on the axle journals 80 and of greater length between their end bearings than the distance between adjacent frame equalizers, rollers supported on the springs adjacent to their ends, upper spring equalizer bars, bearing on said rollers, and 85 spring hangers coupled to said upper spring equalizer bars and to the frame equalizers.

WILLIAM DALTON.

WILLIAM E. WOODARD.
